US00D860230S

(12) **United States Design Patent** (10) Patent No.: **US D860,230 S**
(45) Date of Patent: ** Sep. 17, 2019

(54) **DISPLAY SCREEN WITH GRAPHICAL USER INTERFACE**

(71) Applicant: **NIDEC-SHIMPO CORPORATION**, Kyoto (JP)

(72) Inventors: **Shinya Adachi**, Kyoto (JP); **Masahiro Akamatsu**, Kyoto (JP)

(73) Assignee: **NIDEC-SHIMPO CORPORATION**, Kyoto (JP)

(**) Term: **15 Years**

(21) Appl. No.: **29/626,086**

(22) Filed: **Nov. 15, 2017**

(30) **Foreign Application Priority Data**

May 18, 2017 (JP) 2017-010575

(51) **LOC (12) Cl.** **14-04**

(52) **U.S. Cl.**

USPC **D14/486**

(58) **Field of Classification Search**

USPC D14/485-488, 489-495

CPC G06T 13/80; G06T 15/02; H04L 12/2631;

H04L 43/045; H04L 41/22; G01C 21/36

See application file for complete search history.

(57) **CLAIM**

The ornamental design for a display screen with graphical user interface, as shown and described.

DESCRIPTION

The file of this patent contains a least one drawing executed in color. Copies of this patent with color drawings will be provided by the United States Patent and Trademark Office upon request and payment of the necessary fee.

FIG. 1 is a front view of a display screen with graphical user interface showing a first embodiment of our new design; and,

FIG. 2 is a front view of a display screen with graphical user interface showing a second embodiment of our new design. The dot-dash broken lines illustrate the display screen and form no part of the claimed design.
